Inventor:
J. Brownell Buehler,
By Attorney

UNITED STATES PATENT OFFICE.

JOHN BROWNELL BUEHLER, OF PHILADELPHIA, PENNSYLVANIA, ASSIGNOR TO CONTAINER CORPORATION OF AMERICA, OF CHICAGO, ILLINOIS, A CORPORATION OF DELAWARE.

ROTOR-END GUARD FOR PULP BEATERS AND THE LIKE.

Application filed February 16, 1928. Serial No. 254,708.

My invention is designed to provide improved means for excluding deleterious substances from between the surfaces of relatively moving adjacent members and particularly to exclude solids from between the end of a rotor and the wall of a fluid container in which it rotates or oscillates. My improvements are particularly applicable to, and designed for use in connection with, the rolls 10 of pulp beaters or paper machinery which revolve in a pulpy mass containing rags, strings, slivers, or other solids which commonly twine around the rotor shaft or jam between the rotor ends and adjacent raceway walls with resulting friction, wear, jamming and breakage, necessitating the stoppage of the machine and manual removal of accumulated obstructing material from around the shaft or between the relatively movable surfaces. My 20 invention provides improved means for eliminating or minimizing such clogging of pulp beaters or other machines having rotors revolving in a mixture of liquid and solids by covering the gap between a rotor and the adjacent container or raceway wall by a gasket, preferably made of heavy rope held annularly expanded by a ring fixed to the rotor end or to the container wall, and by admitting to the chamber formed by the rotor end, adjacent 25 wall and gasket a liquid under sufficient pressure to cause a current to flow outwardly through or around the gasket, which is preferably slightly liquid permeable and has an end so mounted as to permit slight expansion 30 and unseating of the gasket to facilitate the outward flow of liquid and to prevent the snubbing of the rotor by the rope. By my improvements the tendency of the pulp solids to accumulate around the rotor shaft and between the rotor ends and adjacent walls is 35 effectually checked and free rotation of the rotor is permitted.

The characteristic features and advantages of my improvements will more fully appear 45 from the following description and the accompanying drawings illustrating the application thereof to a breaker roll of a paper pulp beater.

In the drawings, Fig. 1 is a somewhat dia- 50 grammatic top plan view of a usual type of pulp beater having my improvements applied thereto, the spacing between the rotor ends and container walls and the size of the gas-

kets being somewhat exaggerated for greater clearness of illustration; Fig. 2 is an enlarged 55 fragmentary sectional view illustrating my improvements and taken on the line 2—2 of Fig. 3; and Fig. 3 is an enlarged vertical sectional view on the line 3—3 of Fig. 2.

The drawings illustrate a usual type of 60 pulp beater comprising a casing 1 forming a raceway or container having side walls 2 provided with suitable journal boxes for the reception of a shaft 3 of a roll 4 which may be provided with suitable peripheral beaters. 65 The shaft 3 and roll 4 are connected together by a spline 5 and are rotated through pulleys 3' by suitable driving mechanism not shown.

In accordance with my improvements, a segmental annular ring 6 having a projecting 70 nose or bead 7 is fixed to the peripheral member 8 secured to the closed web or spider 9 at each end of the roll, which is spaced slightly from the adjacent wall 2. The space between the point of each nose 7 and the adjacent wall 75 is closed by a gasket 10 having one end anchored by a clevis 11 in a box 12 on the outer side of the wall 2. The rope gasket 10 is annularly expanded by and completely encircles the bead 7 and its free end passes through 80 the box 12 and out through an aperture in the wall thereof and over a roller 13 on the outside of the wall. A weight 14 suspended from the free end of the rope 10 forms a tension member normally drawing the gasket against 85 the seat formed by the bead 7 but permits the unseating of the gasket should the friction thereon of the rotating bead tend to cause snubbing. The rope gasket is also slightly 90 unseated by the outward flow of water introduced from a suitable source of supply through the inlet 15 to the chamber formed by the side wall 2, roll end 9, ring 6 and gasket 10.

It will be understood that in operation water under pressure is admitted through the inlet 15 and by its outward flow toward the periphery of the roll tends to carry away from the space between the roll end and adjacent wall pulp constituents that would otherwise 100 tend to accumulate between such parts, and the ingress of such pulp constituents between the roll end and wall is positively prohibited by the gasket 10 which imposes no substantial frictional restraint upon the roll and 105 yields by lifting the weight 14 and thereby

frees itself from the seat should the rotation of the bead within the rope tend to cause any snubbing action.

It will further be understood that while it is preferable that the gasket completely encircle the end of the rotor or movable member, this is not essential so long as the gap between the submerged portion of the movable member and the adjacent wall is covered by the gasket.

Having described my invention, I claim:

1. In apparatus of the character described, the combination with a fluid container having a rotor revoluble therein with an end adjacent to a wall of said container, of a gasket closing the gap between the submerged portion of the end of said rotor and said wall.

2. In apparatus of the character described, the combination with a fluid container having a rotor revoluble therein with an end adjacent to a wall of said container, of means for covering the gap between the submerged portion of the end of said rotor and said wall and means for applying fluid pressure outwardly against said means first named.

3. In apparatus of the character described, the combination with a fluid container having a rotor revoluble therein with an end member adjacent to a wall member of said container, of a ring mounted on one of said members, a gasket on said ring, and means for drawing said gasket against said ring.

4. In apparatus of the character described, the combination with a fluid container having a rotor revoluble therein with an end member adjacent to a wall member of said container, of a ring mounted upon one of said members, a gasket on said ring, and means for supplying fluid under pressure between the end of said rotor and the wall of said raceway.

5. In apparatus of the character described, the combination with a fluid container having a rotor revoluble therein with an end member adjacent to a wall member of a raceway, of means for supplying fluid pressure between said members to cause flow outwardly toward the periphery of said rotor.

6. In apparatus of the character described, the combination with a revoluble rotor having

an end adjacent to a wall of a fluid container, of a gasket for closing the gap between the end of said rotor and wall, a device for holding said gasket annularly expanded, means for contracting said gasket against said device, and means for supplying fluid pressure between said rotor end and wall within the gasket.

7. In apparatus of the character described, the combination with a revoluble rotor having an end adjacent to a wall of a fluid container, of a gasket between the end of said rotor and said wall, one end of said gasket being yieldingly supported so as to prevent snubbing of said rotor by said gasket.

8. In apparatus of the character described, the combination with a revoluble rotor having an end adjacent to a wall of a fluid container, of a gasket closing the gap between the end of said rotor and wall, means for anchoring one end of said gasket, means for holding said gasket annularly expanded, and means on the other end of said gasket for yieldingly drawing it into contact with said means last named.

9. In apparatus of the character described, the combination with a revoluble rotor having a closed end and a container having a wall adjacent said closed rotor end, of a segmental ring fixed to said rotor end and provided with a projecting bead, a rope gasket having an end connected with said wall and surrounding said bead to close the gap between it and said wall, a tension member connected with the free end of said gasket, and means for supplying fluid to the space between said wall and rotor end within the periphery of said gasket.

10. In apparatus of the character described, the combination of relatively movable adjacent members, a gasket closing the gap between the submerged portions of said members, and means for admitting fluid to the space between said members within said gasket.

In testimony whereof I have hereunto set my name this 10th day of February, 1928.

JOHN BROWNELL BUEHLER.
